UNITED STATES PATENT OFFICE.

HENRY W. FALKER, OF ASHLAND, PENNSYLVANIA.

ORE AND COAL WASHER.

1,055,730.

Specification of Letters Patent. Patented Mar. 11, 1913.

Application filed October 24, 1911. Serial No. 656,399.

To all whom it may concern:

Be it known that I, HENRY W. FALKER, a citizen of the United States, residing at Ashland, in the county of Schuylkill and State of Pennsylvania, have invented certain new and useful Improvements in Ore and Coal Washers, of which the following is a specification.

This invention relates to ore and coal washers and more particularly to that class of machines in which a jig pan or screen is mounted for oscillation in a liquid receiving tank to effect the separation of slate and other foreign matter from the coal.

The primary object of the invention is to provide a coal washer or jigger, the construction of which is such that the separation of the slate and other foreign matter from the coal may be effected in a more thorough manner and in less time than heretofore.

A further object is to provide a novel form of jig pan or screen, and means for receiving the impact of the slush and coal at the feed end of said pan.

A further object is to provide the jig pan or screen with overhanging side plates which extend partially across the pan at the discharge end thereof and serve to prevent the material from falling between the sides of the pan and the controlling gate and obstructing or otherwise interfering with the operation of the latter.

A further object is to provide the discharge end of the pan with a vertical plate or abutment on which is pivotally mounted a discharge spout, thus to permit the pan to oscillate in the washing tank without interfering with said spout.

A still further object of the invention is generally to improve this class of devices, so as to increase their utility, durability and efficiency.

Further objects and advantages will appear in the following description, it being understood that various changes in form, proportions and minor details of construction may be resorted to within the scope of the appended claims.

For a full understanding of the invention and the merits thereof, reference is to be had to the following description and accompanying drawings, in which:

Figure 1 is a longitudinal sectional view 55 of a coal washer or jigger embodying my

invention; Fig. 2 is a vertical sectional view taken on the line 2—2 of Fig. 1 and looking in the direction of the arrow; Fig. 3 is a top plan view; Fig. 4 is a detail perspective view, showing the stepped frame of the jig 60 pan or screen detached; Fig. 5 is a detail perspective view of one of the side plates of the jig pan or screen detached; Fig. 6 is a perspective view of the hopper.

Corresponding and like parts are referred to in the following description and indicated in all the views of the drawings by the same reference characters.

The improved machine forming the subject matter of the present invention comprises a supporting frame including upper and lower longitudinal sills 5 and 6 connected in any suitable manner by spaced uprights 7. Mounted on the supporting frame, is a stationary washing tank 8, the front end of which is formed by a transverse partition 9, while the rear end thereof is inclined downwardly at 10 in the direction of the bottom 11. Secured to the upper longitudinal sills 5 are bearings 12 in which 70 is mounted for rotation an actuating shaft 13, the latter being provided with spaced hangers 14 having eccentric straps 15 engaging suitable eccentrics 16 on the shaft, as shown. Suspended from the hangers 14, 80 and mounted for both vertical and horizontal movement within the washing tank 8, is a jig screen or pan 17 adapted to receive the coal and slush from a feed spout 18, the latter being pivotally mounted at 19 on the longitudinal sills 5 at the rear end of the 85 jig screen, as best shown in Fig. 1 of the drawings. A second shaft 20 is preferably journaled on the sills 5 and connected with the feed end of the jig screen by spaced 90 loops or hangers 21 so that when the shaft 13 is actuated, a gyratory movement will be imparted to said jig screen.

Interposed between and secured in any suitable manner to the side walls 22 of the jig screen, is a frame 23 of the construction shown in Fig. 4 of the drawings. The side bars of the frame 23 are cut-away to produce a series of steps 24 on which are mounted perforated plates 25 which constitute the bottom of the jig screen. By forming the bottom of the jig screen in this manner, when the pan or screen is operated, the steps 24 will impart a rolling movement 105 to the coal over the bed of slate in the bot- 110

tom of the pan or screen and thus permit the ready discharge of the free coal through a spout 26 at the front of said screen.

The forward end of the frame 23 is provided with a contracted portion 27 terminating in a transverse bar 28 having oppositely disposed lugs 29 for attachment to the lower edge of the side walls 22 of the pan, which lugs are provided with inwardly extending bearings 30 adapted to receive the rock shaft 31 of a controlling gate 32. The controlling gate 32 is provided with a perforated bottom and oppositely disposed side flanges 33, the free ends of the flanges 33 being reduced 15 and extended longitudinally to form spaced arms 34.

Pivottally mounted at 35 with the free ends of the arms 34, are vertically disposed rods 36, the upper ends of which project through 20 guide plates 37 mounted on the upper edges of the side walls of the jig pan and are provided with terminal nuts 38, there being coil springs 39 interposed between the nuts and guide plates 37 for normally and yieldably 25 holding the gate 32 in closed position.

Disposed at the discharge end of the jig pan or screen, is a vertical plate or partition 40 having its upper end inclined downwardly at 41 and its lower end spaced from 30 the transverse bar 28 to produce a discharge opening 42, which latter is normally closed by the gate 32. The plate or abutment 40 is provided with oppositely disposed attaching flanges 43 having perforations formed 35 therein for the reception of bolts or similar fastening devices and by means of which the abutment is rigidly secured to the screen. The inclined portion 41 of the abutment is formed with half bearings 44 adapted to receive 40 trunnions 45 mounted on the spout 26, so as to permit free oscillation of the jig screen or pan within the washing tank, without affecting said spout.

Disposed within the jig pan or screen, are 45 side plates 46 of the construction shown in Fig. 5 of the drawings. Each side plate 46 is provided with an upstanding attaching flange 47 for permanent connection with the adjacent side wall 22 of the pan or screen 50 and a downwardly inclined intermediate portion 48 which overhangs the gate 32 and serves to prevent the material from dropping between the side walls of the pan and said gate and clogging or otherwise interfering with the operation thereof. Each side plate 46 is also provided with a depending flange 49 which overlaps and bears against the adjacent flange 33 of the controlling gate and is rigidly secured to the adjacent ends of the contracted portion 27 of the frame 23, there being a notch 50 formed in the lower edge of the flange 49 to accommodate the rock shaft 31 of the controlling gate. The perforated portion 48 of each 65 side plate is preferably inclined rearwardly

at 51 and gradually merges into the side walls of the pan so as to form in effect a guide and assist in directing the slate and other foreign matter to the discharge opening.

It will here be noted that the lower perforated plate constituting the steps, is interposed between and bears against the depending flanges 49 of the side plates so as to assist in retaining said side plates in position and also to assist in preventing accidental displacement of the adjacent perforated plate 25.

Seated in an opening in the bottom 11 of the washing tank, is a reversible hopper 52 having oppositely disposed extensions 53, one of which projects within the tank, while the other registers with and forms a continuation of an inclined chute 54. Mounted for rotation in the hopper 52, is a sprocket wheel 55, over which passes the sprocket chain 56 of a conveyer, which chain also passes around a similar sprocket wheel 57 secured to a shaft 58 and is provided with spaced flights 59 which serve to remove the slate, slush and other foreign particles in the hopper 52. The hopper 52 is provided with a discharge opening 60 normally closed by a sliding gate 61, to which gate is connected a rod 62 leading to a lever 63, so that by rocking the lever on its pivotal axis, the gate 61 may be moved to open or closed positions.

Arranged parallel with the conveyer 56, is a similar conveyer 64 adapted to receive the coal from a chute 65 and carry said coal to a suitable point of discharge. The conveyer 64 is preferably of less length than the conveyer 56 and is separated from the latter by a longitudinal partition 66 secured to the partition 9, as shown.

Extending inwardly from the opposite side walls of the jig pan or screen, are spaced flanges 67 between which is slidably mounted for vertical movement, a transverse plate 110 or partition 68, the latter being preferably arranged at an angle or inclination to the feed end of the screen and serving to receive the impact of the coal and slush as the latter is fed into the pan or screen. The 115 partition 68 is adjustable vertically of the jig pan or screen by means of threaded bolts 69 connected with said partition and extending through a transverse bar 70.

It will here be noted that the gate 32 is movable to open or partially open position by the weight of the bed of slate in the bottom of the jig pan or screen, thus effectually preventing the accumulation of slate at the discharge opening and interfering with the proper operation of the machine, the springs 39 serving to return the gate to closed position when the latter has been relieved of the weight of the bed of slate, as will be readily understood. It will also be noted that the 130

hopper 52 is reversible and forms a continuation of the inclined wall 10 of the washing tank so that the slush, as well as the slate and other foreign matter deposited in the tank 8, will be directed into the hopper and thence conducted by means of the conveyer 56 to a suitable point of discharge. Thus it will be seen that when the material is introduced through the spout 18 into the jig pan 10 or screen, the slate will gravitate to the perforated bottom of said pan, while the coal will roll over the top of the bed of slate and be discharged through the spouts 26 and 65 and deposited on the conveyer 64, the vertical movement of the pan in the washing tank, causing the water to effect a thorough washing of the coal and the separation of the slate therefrom. The stepped portion 24 of the pan has the effect of kicking or feeding the coal in a forward direction and also has a tendency to turn the light particles of slate within the jig pan and present said slate edge down, thus permitting the separation of flat or flake slate as well as cube slate. As the slate accumulates on the perforated bottom of the pan, the weight of the slate will open or partially open the gate 32 and allow the slate to drop by gravity into the tank 8 and thence into the hopper 52 so as to be taken up by the conveyer 56. During the gyratory movement of the jig pan or screen, the free coal discharged through the spouts 26 and 65 will be deposited on the conveyer 64 and thence directed to a suitable point of discharge, as before stated.

Having thus described the invention, what is claimed as new is:

1. In combination, a tank, a jig screen suspended within the tank and provided with a discharge opening, a gate arranged at said discharge opening, perforated plates secured to the side walls of the jig screen and overlapping the gate, and means for vertically reciprocating the jig screen.

2. In combination, a tank, a jig screen suspended within the tank and having its discharge end provided with an opening, a yieldably supported gate serving to normally close said opening, perforated plates secured to the side walls of the screen and overlapping the side edges of the gate, and means for vertically reciprocating the jig screen.

3. In combination, a tank, a jig screen suspended within the tank and having its discharge end provided with an opening, an abutment disposed at said opening, a discharge spout connected with the abutment, a spring actuated gate serving to normally close the opening in the screen, and perforated plates secured to the opposite sides of the jig screen and overlapping the gate.

4. In combination, a tank, a jig screen suspended within the tank and having its

discharge end provided with an opening, a gate pivotally mounted at said opening and provided with upstanding flanges, a vertical abutment forming one wall of the opening, a discharge spout, perforated side plates secured to the jig screen and provided with depending flanges overlapping the flanges on the gate, and means for vertically reciprocating the jig screen.

5. In combination, a tank, a jig screen suspended within the tank, a frame forming a part of the jig screen and having its rear end stepped and its forward end reduced and provided with bearings, perforated plates secured to the stepped portion of the frame and constituting the bottom of the jig screen, a gate journaled in said bearings and having spaced arms, an abutment, a discharge spout pivotally connected with the abutment, means connected with the arms of the gate for normally and yieldably holding the latter in closed position, and means for vertically reciprocating the jig screen.

6. In combination, a tank, a jig screen suspended within the tank, a frame forming a part of the jig screen and having its forward portion provided with bearings, a gate pivotally mounted in said bearings and having spaced upstanding flanges, an abutment disposed at the discharge end of the jig screen and bearing against said flanges, means operatively connected with the free end of the gate for normally and yieldably holding the latter in closed position, perforated side plates secured to the jig screen and having depending flanges overlapping the flanges on the gate, said depending flanges being provided with notches to accommodate said bearings, and means for vertically reciprocating the jig screen.

7. In combination, a tank, a jig screen suspended within the tank, a frame forming a part of the jig screen and having its rear end stepped and its forward end contracted and provided with a transverse bar having attaching lugs for engagement with the lower longitudinal edges of the side walls of the jig screen and provided with inwardly extending bearings, perforated plates engaging the stepped portion of said frame and constituting the bottom of said jig screen, a gate journaled in said bearings, a vertical abutment arranged at the discharge end of the jig screen, a discharge spout leading from said abutment, means for normally and yieldably holding the gate in closed position, side plates secured to the side walls of the jig screen and overlapping the gate, and means for vertically reciprocating the jig screen.

8. In combination, a tank, a jig screen suspended within the tank and provided with a discharge opening, a gate arranged at the discharge opening, perforated plates

- secured to the side walls of the jig screen and extending inwardly and downwardly therefrom at said gate, and means for vertically reciprocating the jig screen.
- 5 9. In combination, a tank, a jig screen suspended within the tank and provided with a discharge opening, a horizontally disposed gate fitting in said discharge opening, plates secured to the walls of the jig screen
- 10 and having portions thereof inclined downwardly in the direction of the gate and their

free ends overlapping said gate and terminating near the surface of the same, and means for vertically reciprocating the jig screen.

In testimony whereof, I affix my signature in presence of two witnesses.

HENRY W. FALKER. [L.S.]
